Maxwell J. Martell
ATTORNEY

UNITED STATES PATENT OFFICE

MAXWELL J. MARTELL, OF BROOKLYN, NEW YORK; GEORGE MARTELL ADMINISTRATOR OF SAID MAXWELL J. MARTELL, DECEASED

DISPLAY DEVICE

Application filed January 31, 1931. Serial No. 512,587.

The present invention relates to display stands of a type used in window advertising and the like, and, in particular, to display stands of a type which can be rolled up when not on display, and also rolled for the purpose of distributing or mailing.

An important advantage of a collapsible display stand over one which is mounted on a stiff backing is that it can be rolled up for the purpose of distributing, mailing and storing to the thickness of a mailing tube, although the flat dimensions may be of any requirement for window advertising.

A further advantage is that a flat package having an easel portion for support, folded upon the back, frequently requires a larger size carton than may be distributed by parcel post, whereas such a display, if rollable into a compact package, may be mailed without difficulty.

Heretofore, so far as I am aware, it has been customary in distributing printed matter which is to be exhibited in a store window, or the like, for advertising purposes to furnish the display either mounted on a stiff backing or printed directly on such backing. To this type of display there has usually been glued or attached a separate easel for support which is carried upon the back thereof.

The difficulty with such a display is that frequently the size requirement exceeds the parcel post size limitations and thus the display cannot be transmitted through the mails. This is a serious disadvantage and prevents efficiency in distributing and handling. Further, with the stiff backing on a display an extra wrapping and extra container is required for distribution, and such extra wrapping or container frequently exceeds or equals the cost of the display itself.

However, according to my present invention, the display stand when ready for distribution is rolled inside of a container which becomes the supporting easel when the device is assembled for display purposes. The display, it is thus seen, can be rolled, and when provided with a plain wrapper or inserted into a mailing tube at the discretion of the advertiser is in condition for mailing

or filing for future use. For display purposes the arrangement may be unrolled and after the easel has been properly affixed to the display plaque in the simple manner to be hereinafter set forth, it gives all the desirable appearance of a perfectly flat and rigid display and supports itself in an upright position.

Another advantage is that this display stand will, when assembled, remain in a fixed upright position without any other support than that which is supplied by its own wrapper or easel.

A further objective is to provide a dependable means for the support in keeping the display in an upright position.

A further advantage and object of my invention is to provide, in conjunction with the rollable and collapsible display, a means whereby when the display is used it may assume a rigid form so as to have all of the desirable appearances of a fixed and rigid display. According to a preferred form of my invention, as will be hereinafter described by making reference to the accompanying drawing, I have provided an arrangement wherein the display sheet has carried along opposite edge portions thereof supporting members between which an easel or supporting portion may be positioned so as to hold the arrangement in a taut stretched position. In order to satisfy the space requirement, I have so arranged the easel portion that it may be rolled and wrapped about the display plaque in shipping or mailing, and thus require very little additional space, and, at the same time, provide a rigid or semi-rigid container within which the display proper is inserted.

According to previous notations wherein the easel is inserted between the top and the bottom cross members, there has been provided on each side of the section so inserted, an extra portion of easel stock which when bent backwards in rightangular position and held so by means of a specially adjusted lock permits the display to stand firm wherever placed.

Other objects of my invention are to provide a display stand for advertising and simi-

lar purposes which is of a convenient size to handle and ship; to provide a display stand which is convenient to assemble; and to provide a display device which is simple 5 in its construction and arrangement of parts as well as being inexpensive and convenient to manufacture.

Still other and ancillary objects and advantages of this invention will become apparent and easily recognized by making reference to the accompanying drawing in connection with the following specification.

By the drawing, Fig. 1 illustrates a rear view of my display stand as assembled; Fig. 15 2 illustrates the display stand as rolled into a compact package and surrounded by the supporting easel; Fig. 3 illustrates the supporting easel prior to the time of rolling; Fig. 4 illustrates a sectional view of the display stand taken on the line 4—4 of Fig. 1; Fig. 5 illustrates a section through a portion 20 of the display stand and one of the edge supporting members; and, Fig. 6 is a sectional view to show corrugated material used for the supporting easel.

Now making reference to the accompanying drawing, the display sheet 1, which is preferably printed or lithographed and of approximately the same weight used for 25 billboard advertising and of a size stipulated by the advertiser, has a supporting member 3 formed of three separate battens or strips of material 5, 7 and 9 suitably fastened thereon so as to form a grooved or slotted portion 30 6 when fastened together. The groove or slot 6 is focused by means of the strips or battens 5 and 9 extending laterally out beyond the batten 7. These various strips or battens may be formed from cardboard strips 40 fastened to the top and bottom of the printed sheet by staples or may be of any other suitable light weight material suitably fastened or glued to the sheet of advertising material 1. Of course, it will be obvious that the 45 supporting member 3 may be a single piece of material appropriately slotted as above suggested.

For the purpose of supporting the sheet when it is unrolled, I have provided an easel 50 member, support or stand 11, shown more particularly by Fig. 3, which, as will hereinafter be described, is adapted to be carried or supported in the slots 6 and 8 formed from the supporting members or battens 5, 55 7, 9 and 5', 7', 9' which are fastened to opposite edge portions of the display sheet.

The easel portion of my device preferably consists of a member 13 capable of being rolled as shown by Fig. 2 to surround the 60 rolled sheet 1. The easel or support member 13 is provided at each end with tongue portions 15 and 17 respectively for engagement with the slots 6 and 8, and, for example, the tongue portion 15 is adapted to fit in the slot 6 of the support members or

battens 3 while the tongue portion 17 fits within the slot 8 formed from the supporting battens 3'. To provide a more rigid support surface the easel 13 is formed of corrugated or other similar and suitable material having the characteristic of being easily rollable in one direction and substantially rigid in a second direction. This provides a surface for support which is better able to withstand wear and to be more serviceable in mailing. 70 In assembling the display stand the tongue portion 15 of member 13 is first positioned in slot 8 and then the tongue 17 is placed in the cutaway portion 19 of the slot 6. The easel or support member may then be moved within slots 6 and 8 longitudinally of the sets of supporting members or battens 3 and 3' until it is in the position shown by Fig. 1.

As so arranged, the supporting portions 21 and 23 of the supporting element, easel or stand 13 extend externally of the lower supports or battens 9' and when curved to a position such as is shown by Fig. 1 form a support for the entire arrangement.

Where desired, and where the support 90 easel or stand is formed of material of sufficient strength and rigidity, the slot formed by the upper support members or battens 5, 7 and 9, or by the lower supporting members or battens, or both, may be so arranged as to 95 vary in depth throughout the length thereof, as indicated by widths *a* and *b* on Fig. 1, so that as the supporting easel or stand is moved from right to left, looking at Fig. 1, the sheet of material 1 carried by the end 100 supporting members 3 and 3' may be stretched in any suitable manner. Also, where desired, the supporting portions 21 and 23 of the support element or easel 13 may be tapered so that they will, when rolled to the position shown by Fig. 1, permit the display sheet 1 to be tipped or tilted to a more suitable angle than perpendicular to the surface upon which the lower element 3' and supporting easel rests so that it may be 105 viewed in a more convenient manner.

In order to fasten the supporting stand or easel 13 in its opened or rolled position for display purposes, I have provided what has been herein termed a hinge or locking member. This lock consists preferably of a wing portion 25 and a cutaway or slotted portion 27. The wing portion of the locking device consists preferably of the same material as forms the supporting element 15 and is 115 formed merely by cutting in a portion of the member a sort of T-shaped section which may be pressed away from the supporting material. In order to permit the wing or T-shaped portion 25 to be bent frequently 120 without breaking away from the supporting member 15, I have preferably provided a hinge 29 of any flexible cloth or the like which may be fastened to both the fixed part of the supporting easel or element 130

15 and the wing portion 25 thereof. Upon opening and bringing the member 15 to the position shown by Fig. 1, the wing portion of the locking device is suitably pressed away 5 from the member 15 in a manner such as will be obvious from examination of Fig. 1. Upon rolling out of the easel to the curved formation of Fig. 1, the wing member 25 is inserted in the slot 27 and is there held securely so 10 as to maintain the easel in opened position.

At such times as the display is no longer required for advertising purposes, it may be readily disassembled and folded in the manner shown by Fig. 2. In the folded state the 15 display is in suitable form both for storing and for shipping.

The many advantages of such an arrangement will, of course, be obvious to those skilled in the art to which the invention relates, and it will be obvious that many changes and improvements may be made herein without departing from the spirit of the invention as herein defined. I, therefore, believe my invention should be construed in 25 its generic sense and limited only in so far as the scope of the hereinafter appended claims necessitates.

Having now described my invention, what I claim and desire to secure by Letters Patent 30 is the following:

1. A collapsible display stand comprising a rollable display sheet having a supporting element provided with a slot therein extending across opposite edge portions of the 35 sheet, a supporting easel having tongue portions on each end for mounting within said slotted member for supporting said sheet and having an elongated base portion flexible in one direction and rigid in a direction corresponding to the height thereof to provide for 40 rolling said easel backward from said sheet, and means for fastening said easel in said rolled position.

2. A readily mailable display device comprising, in combination, a rolled display sheet and a display stand rigid in one direction to support the display sheet and rollable in a second direction so as to form, when 45 rolled, a mailing carton for the display sheet.

3. A display stand comprising a display sheet, an elongated slotted member extending across each end of said sheet, one of said members having a portion thereof recessed 50 intermediate the ends thereof, and a supporting easel adapted to be positioned within said recessed portion and moved to a position within said slotted member so as to support said sheet in a rigid manner.

4. A display stand comprising a display sheet, an elongated slotted member of progressively varying depth extending completely across each end of said sheet, a supporting 55 easel adapted to be positioned within said slotted member and moved to a position so as

to support said sheet in a rigid manner, and means for fastening said easel in a position to support said sheet.

5. A display stand comprising a display sheet, an elongated slotted end support member extending across each end of said sheet, and at least one of said slotted members being of varying depth from end to end and one of said members having a portion thereof recessed, a supporting easel adapted to be positioned within said recessed portion and moved to a position within said slotted members so as to support said sheet in a rigid manner, and a locking device for maintaining 70 said easel in position to support said display sheet.

6. A display stand comprising a display sheet, a plurality of supporting members carried upon each end of said sheet, said supporting members being so arranged as to form a slotted supporting element having a slot of progressively varying depth from end to end, one of said supporting members having a recessed portion therein, and a supporting easel adapted to be positioned within the recessed portion of said support member and moved within said slotted members to a position such as to support and stretch said display sheet.

7. A collapsible display comprising, in combination, a rollable display sheet, a plurality of supporting members secured to opposite edge portions thereof in such manner as to permit the display sheet to be rolled, and an easel member rigid in one direction to space the supporting members for displaying the sheet and rollable in a second direction for providing, upon dis-assembling from the support elements, a carton for housing the display sheet and end supporting elements in rolled position.

8. A display stand comprising a display sheet, a plurality of supporting members carried upon each end of said sheet, said supporting members being so arranged as to form a slotted supporting element having a slot of varying depth, one of said supporting members having a recessed portion therein, an easel having supporting members at one end thereof and provided with tongue portions on the opposite end thereof adapted to be positioned within the recessed portion of said support member and moved within said slotted elements to a position such as to support and stretch said display sheet, means provided by said supporting members of said easel for supporting said entire display when said members are curved relative to said display sheet, and means for fastening said easel supporting members in said curved position.
